(57) **CLAIM**

We claim the ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof; and,

FIG. 11 is the eleventh image thereof.

The dot dash lines in the figures represent an unclaimed boundary line and form no part of the claimed design.

The appearance of the animated user interface sequentially transitions between the images shown in FIGS. 1-11. The process or period in which one image transitions to another forms no part of the claimed design.
